SCALP MASSAGING DEVICE

Martin Edward Hempel, Berwyn, Ill.

Application August 3, 1938, Serial No. 222,763

6 Claims. (Cl. 128—63)

The invention relates to scalp massaging devices.

In baldness it has been found that the scalp usually has a distinctive region of tenseness surrounded by a wreath of thin hair, and that this diminution in mobility produces bald areas. It has also been found that the growth of the skull produces the stretching of the bony skull cap which compresses the blood vessels supplying the scalp so that the entire cellular tissue supplying hair formation becomes injured and degenerates and the hair follicles suffer disturbance of nutrition, and baldness results. It has also been ascertained that a properly carried out relaxation of the scalp combats the loss of hair and, in some cases, restores new hair to bald spots. Massage movements, for the purpose of stretching the scalp upwardly from the region where the hair-roots have not been completely destroyed, restores circulation and produces relaxation, and is effective in the treatment of baldness.

The object of the invention is to provide a massaging apparatus which is particularly adapted to be manipulated so as to massage the scalp from the sides of the scalp in an upward direction to loosen and relax the scalp and force circulation from the tissue which is still active with circulation to the tense portions of the scalp.

Other objects of the invention will appear from the detailed description.

The invention consists in the several novel features which are hereinafter set forth and are more particularly defined by claims at the conclusion hereof.

In the drawing: Fig. 1 is a side elevation of a massaging device embodying the invention. Fig. 2 is an end elevation. Fig. 3 is a longitudinal section. Fig. 4 is a section on line 4—4 of Fig. 3. Fig. 5 is a section on line 5—5 of Fig. 1. Fig. 6 is a detail perspective of a pair of flexible massaging bands. Fig. 7 is a perspective of a modified form of massaging band.

The invention is exemplified in a device which comprises a housing or frame, a series of endless flexible massaging bands or belts, and power-driven gearing for driving the bands or elements. The housing is preferably integrally formed with sidewalls 10, inclined and curved end-walls 11, and an extension 12 of suitable contour to provide a handle whereby the device may be manipulated over the scalp. The endless bands extend around and between a drive-roll 14 and an idler-roll 13. Each of these rolls is formed with annular grooves 15 for the massaging bands respectively.

The massaging bands are made of rubber so they are flexible to conform to the scalp and are arranged in pairs 16, 17 which are provided with oppositely inclined ribs 18.

The opposite inclination of the ribs causes them to exert a lateral pressure or kneading effect on the portion of the scalp engaged thereby. The bands are spaced apart to allow the compressed portions of the scalp to pass between the bands and prevent the accumulation of the tissue in front of the ribs. The lower portion of sides 10 of the frame are cut away to expose the lower reaches of the bands 16 and 17 for engaging the scalp and being flexed thereby. The lower reaches of the bands between rolls 13 and 14 will be flexed by the scalp conformably to the contour of the scalp when the device is manipulated thereover.

Idler-roll 13 is mounted on a shaft 19 which is slidably mounted in slots 20 and held in tighteners 21 which are provided with screws and nuts 22 whereby the roll 13 may be adjusted to or from the drive-roll 14 to loosen or tighten the bands, so the lower reaches of the bands will be flexible in the desired degree for conformation to the scalp.

Gearing for driving roll 14 to drive the bands 16, 17 is mounted in the housing and comprises a shaft 25 which is fixed to roll 14 and is journaled in sides 10 of the housing; a sprocket-wheel 24 which is secured by a pin to shaft 25; a sprocket-wheel 26 fixed to a shaft 27 which is journaled in the sides 10 of the casing; a sprocket-chain 28 between sprockets 26 and 24; and a gear 30 fixed to shaft 27. Preferably an electric motor 32 for driving this gearing has its casing mounted on one of the casing end-walls 11 and drives a worm 31 which engages gear 30. Motor 32 is supplied with current by a conductor-cord 33, one end of which is usually provided with a plug for connection to an electric socket. If desired, gear 30 may be driven from a stationary motor through a flexible shaft. The gearing is driven to operate the bands in the direction of the arrow shown in Fig. 3.

In the operation of the device, the operator grasps the handle 12 and brings the lower reaches of the endless belts 16 and 17 in contact with the sides or back of the scalp and moves the casing upwardly toward the top of the scalp with the roller 14 in advance of the roller 13. The lower reaches of the belt will travel upwardly to produce a massaging effect from the sides and back of the head toward the top. The side 10 adjacent sprocket 24 is provided with

an inward extension 10^a (Fig. 5) to prevent hair from being caught in the lower portion of said sprocket and the chain. The device is used mainly on thinly haired scalps or bald portions of scalps for the treatment of baldness. The massaging effect is desired mainly over the bald spots and the hair immediately surrounding them. In manipulating the device in the region of the hair, the portions of the bands adjacent the sprocket at the front of the frame may be raised slightly away from the scalp and the massaging produced by the middle and rear portions of the bands.

The lower reaches of the belt, being flexible, will conform to the curvature of the scalp and the oppositely inclined ribs 18 will engage the scalp and, through their massaging effect and laterally deflecting action, induce mobility in the tissue which is under tension and has become hard and thin. This massaging treatment restores the circulation, has a tendency to reduce the adhesion between the aponeurosis and the hair-bearing skin of the head. The relaxation produced, when carried on continuously, serves to prevent the tension which causes the skin to become hard and thin and to degenerate the blood vessels, the cellular tissue and the nutrition of the hair follicles and wherever the hair-roots have not been completely destroyed, relaxes the tension and produces a new formation of hair.

The front portion of the housing 11 is extended around, and encloses, the front of roller 14 and the portions of the bands thereon to guide or deflect the hair under the belts, as the housing is advanced over the scalp and the bands are driven in the direction indicated by the arrow in Fig. 1. In these movements, the bands press the hair against the scalp and prevent it from being entangled in the mechanism of the device.

A modified form of massaging band comprising a flexible strip 35 and bristles 36 projecting therefrom, is shown in Fig. 7.

The invention exemplifies a massaging device comprising endless bands which are flexible to conform to the scalp and mechanism for driving the bands, which can be manipulated from the sides of the scalp toward the top to stimulate circulation from the region of the wreath of hair usually remaining toward the zone which has become rigid and tense. The invention also exemplifies a device which may be used as a preventive of baldness and to induce new formation of hair where the hair-roots have not been completely destroyed.

The invention is not be understood as restricted to the details set forth, since these may be modified within the scope of the appended claims, without departing from the spirit and scope of the invention.

Having thus described the invention, what I claim as new and desire to secure by Letters Patent is:

1. In a scalp massaging device, the combination of a portable housing provided on the top thereof with a grip whereby it may be manually manipulated over the scalp, a pair of rolls mounted in the housing, a series of relatively narrow transversely aligned endless bands of rubber provided with massaging elements on their outer faces, having their lower reaches free to flex longitudinally, the bands being sufficiently flexible to permit said reaches of the bands to yield longitudinally and independently 75

of one another so they will conform to the convexity of, as the device is moved over and pressed against, the scalp, and power-operated means carried by the housing for continuously driving one of the rolls in one direction.

2. In a scalp massaging device, the combination of a portable housing provided on the top thereof with a grip whereby it may be manually manipulated over the scalp, a pair of rolls mounted in the housing, a series of relatively narrow transversely aligned endless bands of rubber, the alternate bands being provided with oppositely oblique massaging elements on their outer faces adapted to knead the scalp transversely, and having their lower reaches free to flex longitudinally, the bands being sufficiently flexible to permit said reaches of the bands to yield longitudinally and independently of one another so they will conform to the convexity of, and as the device is moved over and pressed against, the scalp, and power-operated means carried by the housing for continuously driving one of the rolls in one direction.

3. In a scalp massaging device, the combination of a portable housing provided on the top thereof with a grip whereby it may be manually manipulated over the scalp, a pair of rolls mounted in the housing, a series of relatively narrow transversely aligned endless bands formed of rubber and extending around said rolls and provided with massaging elements on their outer faces, the housing being provided at its front end with means extending substantially to the plane of the lower reaches of the bands 35 to prevent the hair from being carried around the front roll by the bands, and power-operated means carried by the housing for continuously driving one of the rolls in one direction.

4. In a scalp massaging device, the combination of a portable housing provided on the top thereof with a grip whereby it may be manually manipulated over the scalp, a pair of rolls mounted in the housing, a series of relatively narrow transversely aligned endless bands 45 formed of rubber and extending around said rolls and provided with massaging elements on their outer faces, a wheel on the front roll, an endless driving element enclosed within the housing and extending around the wheel for driving the front roll, the housing being provided at its front end with means extending substantially to the plane of the lower reaches of the bands to prevent the hair from being carried around one of the rolls by the bands, and 55 with an inwardly extending guard around the portion of the element around the front roll, and power-operated means carried by the housing for continuously driving said element in one direction.

5. In a scalp massaging device, the combination of a portable housing provided on the top thereof with an integral grip whereby it may be manually manipulated over the scalp, a pair of rolls journaled in the housing, a series of relatively narrow transversely aligned endless bands of rubber extending around the rolls and provided with massaging elements on their outer faces, a motor mounted on the outside of the housing under one end of the handle, gearing 65 for driving the front roll, comprising a wheel driven by the motor, a wheel on the front roll, and an endless element extending around said wheel and roll, said wheels and element being enclosed within the housing.

6. In a scalp massaging device, the combina-

tion of a portable housing provided on the top thereof with an integral grip whereby it may be manually manipulated over the scalp, a pair of rolls journaled in the housing, a series of relatively narrow transversely aligned endless bands of rubber extending around the rolls and provided with massaging elements on their outer faces, a motor mounted on the outside of the housing under one end of the handle, gearing for driving the front roll, comprising a wheel 10 driven by the motor, a wheel on the front roll,

and an endless element extending around said wheel and roll, said wheels and element being enclosed within the housing, the housing being extended substantially to the plane of the exposed reach of the bands and around the portion of the element passing around the wheel on the front roll for preventing hair from being carried around the front roll and by said element.

MARTIN EDWARD HEMPEL.
